(57) **CLAIM**

The ornamental design for a portion of electrical connector, as shown and described.

DESCRIPTION

FIG. 1 is a front perspective view of our new design for a portion of electrical connector;

FIG. 2 is another front perspective view thereof;

FIG. 3 is a front elevation view thereof;

FIG. 4 is a back elevation view thereof;

FIG. 5 is a right-side elevation view thereof;

FIG. 6 is a left-side elevation view thereof;

FIG. 7 is top plan view thereof;

FIG. 8 is a bottom plan view thereof; and,

FIG. 9 is a back perspective view thereof.

In the drawings, all areas or surfaces that include shade or contour lines are part of the claimed design. The broken lines in the drawings are included for the purpose of illustrating environmental subject matter and form no part of the claimed design.
